(57) **CLAIM**

The ornamental design for a base station for computer communication network, as shown and described.

DESCRIPTION

FIG. 1 is a front view showing a base station for computer communication network according to the present invention; FIG. 2 is a rear view showing the base station of FIG. 1; FIG. 3 is a top plan view showing the base station of FIG. 1;

FIG. 4 is a bottom plan view showing the base station of FIG. 1;

FIG. 5 is a right side view showing the base station of FIG. 1, the left side view being a mirror image of the right side view; and,

FIG. 6 is a front perspective view showing the base station of FIG. 1.
